UNITED STATES PATENT OFFICE.

FREDERICK L. G. STRAUBEL, OF GREEN BAY, WISCONSIN.

DRAWER OR FILE-BOX.

SPECIFICATION forming part of Letters Patent No. 586,512, dated July 13, 1897.

Application filed October 23, 1896. Serial No. 609,843. (No model.)

To all whom it may concern:

Be it known that I, FREDERICK L. G. STRAUBEL, a citizen of the United States, residing at Green Bay, in the county of Brown and the 5 State of Wisconsin, have invented a new and useful Improvement in Drawers for Cabinet Letter or Paper Files, of which the following is a specification.

My invention relates to an improvement in 10 drawers or file-boxes in which spring-compressors are employed to hold the sheets in layers flat against the bottom of the drawer.

The object of my invention is to provide 15 convenient facilities for filing and ready access to letters or such papers as are filed 20 therein. I attain this object by the mechanism and construction as illustrated in the accompanying drawings.

Figure 1 is a vertical section of the drawer, 25 showing the right-hand inner side. Fig. 2 is a top view of the right-hand rear corner, showing the combined coiled spring and hinge of the compressor. Fig. 3 is a perspective view of the drawer withdrawn from the cabi- 30 net or receptacle to a position ready to receive letters or papers or for the examination of those filed therein.

Similar letters refer to similar parts in the several views.

35 Cabinet letter or paper files are usually made with a number of compartments or receptacles to receive drawers or file-boxes. A A A represent the walls of one of these compartments or receptacles, B B the side walls of the drawer, and C the back wall.

Up to the present time to my knowledge 40 cabinet letter-files generally in use are provided with some kind of spring-compressor and indexed leaves in the drawers, and these I also propose to use, as without them the drawers would not be considered as complete for the purpose intended.

Wherein my invention differs from others 45 is that the spring-compressor is hinged and secured at the back wall of the drawer instead of at the front wall, and the index-leaves are inserted, having their lettered index-tabs at the front wall, and may be hinged or otherwise secured at the back wall. The front wall is 50 hinged at or near its lower edge, and in connection with the intermediate rods and levers the compressor is operated with the move-

ment of the hinged front. As will be seen in Fig. 3, this arrangement with the indexed leaves toward the operator permits of convenient access to the contents of the drawer, and letters or papers may be readily filed therein without the drawer being entirely withdrawn or removed from the cabinet. A suitable stop may be arranged to prohibit the further withdrawal of the drawer when in this position.

With a file-drawer such as I describe the operator can with one hand withdraw and prepare it while his other hand is holding the papers he desires to file.

D represents the loop of the spring-compressor, and E E its coiled springs, which also act as hinges to the compressor and are secured to the back wall of the drawer near 70 its upper edge by the brackets F F, and pins from these brackets pass through the coiled springs and are secured to the side walls of the drawer. I give preference to this construction, although it can be modified in various ways.

The operation of the compressor which I attain in my invention is particularly shown in Fig. 1.

The ends of the wire used in the construction of the spring-compressor, projecting from the coiled springs near the side walls, extend back from the coils, one end being shown in the several views. The loop D of the compressor bears upon the contents of the drawer 85 and also forms the connection between the coils E E. To the projecting end H, from the coils of the compressor, is hinged or jointed the rod a and to this the rod or lever b and the latter secured at its lower end to the side 90 wall of the drawer by a pivot or pin c. The connecting-rod I is connected with the rods or rod and lever a and b and at that end is jointed to them at or near d and its other end jointed and secured to the inner side of the 95 hinged front J. The front J, when raised to an upright position, as in Fig. 1, by the action of the rods and lever I, b, and a in connection therewith, will force the loop of the spring-compressor down upon the contents of the 100 drawer, and the compressor will remain locked in that position until released by the outward motion of the hinged front J. The outward motion of the front J does not only release,

but will also raise, the compressor-loop D, as shown by the dotted lines in Fig. 1, permitting access to the contents of the drawer, as shown in Fig. 3.

5 The coils E E should be made to provide for sufficient flexibility to the compressor-loop D to allow the contents of the drawer to be of various thicknesses when the compressor is forced down upon them by the rods and lever 10 in connection with the front J.

In forcing down the compressor-loop upon the contents of the drawer by the action as above described a corresponding pressure is retained at the extended wire end from the 15 coils at H down upon the rods or rod and lever a and b, and as these are forced back somewhat out of line with the joints at H and c, at joint d by the rod I, when the drawer is being closed or the front J placed upright, a 20 complete lock is formed by the rods and lever in this position to the compressor, which can only be removed by the reverse motion of the front J in connection with the rod I.

The front J, after being placed in an upright 25 position, will be held there against the ends of the side walls of the drawer to the extent of the tension of the springs upon the rods in connection therewith.

I cannot confine myself strictly to the arrangement of the rods and lever and the direction from the coils and the extension of

the projecting wire end H, as the combination can be modified in various ways and have the same or a similar effect upon the compressor and the hinged front J.

The rods and lever may be recessed into the side walls of the drawer or may be completely concealed within these walls, so as not to be of any obstruction to the contents of the drawer.

I am aware that prior to my invention drawers for cabinet letter or paper files have been made with spring-compressors and drawers with loose or hinged fronts. I do not therefore claim this combination, broadly; 45 but

What I do claim as my invention, and desire to secure by Letters Patent, is—

In a drawer for cabinet letter or paper files, the rod I in connection with the hinged front J, the rod a in connection with the spring-compressor, and the rod or lever b in connection with the rods I and a, forming a combination of connecting-rods between and arranged to act upon, the spring-compressor 55 and the hinged front J, substantially as and for the purpose described and set forth.

FREDERICK L. G. STRAUBEL.
